US00D655693S

(12) **United States Design Patent**
Silvestri et al.

(10) **Patent No.:** **US D655,693 S**
(45) **Date of Patent:** **** Mar. 13, 2012**

(54) **EARPIECE**

(75) Inventors: **Ryan C. Silvestri**, Franklin, MA (US); **Eric M. Wallace**, Chelmsford, MA (US); **Kevin P. Annunziato**, Medway, MA (US); **Ian M. Collier**, Cambridge, MA (US); **Michael Monahan**, Southborough, MA (US)

(73) Assignee: **Bose Corporation**, Framingham, MA (US)

(**) Term: **14 Years**

(21) Appl. No.: **29/385,663**

(22) Filed: **Feb. 17, 2011**

International Search Report and Written Opinion dated Oct. 27, 2011 for International application No. PCT/US2011/048233.

Primary Examiner — Paula Greene

(74) *Attorney, Agent, or Firm* — Bose Corporation

(57) **CLAIM**

The ornamental design for an earpiece, substantially as shown and described.

DESCRIPTION

FIG. 1 is a perspective view of an audio system as seen from the front, top and left side;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dotted line portions of the drawings represent environmental structure only and do not form part of the claimed design.

1 Claim, 4 Drawing Sheets

See application file for complete search history.
